UNITED STATES PATENT OFFICE.

HENRY SEELIGSON, OF DALLAS, TEXAS.

LEAF OR INSERT FOR BOOKS AND THE LIKE.

1,114,920.

Specification of Letters Patent. Patented Oct. 27, 1914.

Application filed February 8, 1913, Serial No. 746,998. Renewed August 11, 1914. Serial No. 856,286.

To all whom it may concern:

Be it known that I, HENRY SEELIGSON, a citizen of the United States, residing at Dallas, in the county of Dallas and State of Texas, have invented certain new and useful Improvements in Leaves or Inserts for Books and the like, of which the following is a specification.

This invention relates to new and useful improvements in leaves or inserts for books and the like.

The object of the invention is to provide a printed sheet embodying certain novel features arranged so that it may be bound in a book or catalogue as a leaf or page thereof or placed therein as an insert.

A very important object is the production of a leaf or insert in which is combined an envelop or postal card associated with an order blank in such a manner that while the envelop or postal card and order blank are attached to the sheet or leaf forming a part thereof, they may be readily detached therefrom and immediately used without the use of adhesives, clips, etc.

A further feature resides in the provision of a leaf or insert of the character described which may be bound or placed in a book or catalogue without causing the same to become bulky or distorted; also the provision of a leaf or insert so arranged that when the parts are detached therefrom, the binding will not in any way be disturbed.

Another object is to provide a printed sheet including an envelop or postal card and order blank so arranged that when said envelop or postal card and order blank are detached from the sheet, a permanent portion or portions of the same will be left intact, and upon which information or data which it is desired to retain in the book or catalogue is printed.

A still further object of the invention is to provide a leaf or insert of the character described which will be efficient, durable, and simple and inexpensive to produce, also one planned to be operative under all conditions.

With the above and other objects in view, the invention has relation to certain novel features of construction and operation, examples of which are described in the following specification and illustrated in the accompanying drawings, wherein:

Figure 1 is a face view of the leaf or insert,

Fig. 2 is an edge view of the same, Fig. 3 is a face view of a modified form, Fig. 4 is an edge view of the same, Fig. 5 is a face view of another form, Fig. 6 is an edge view 60 of the form shown in Fig. 5, Fig. 7 is a face view of still another form, Fig. 8 is an edge view of the postal card of Fig. 6, folded, Fig. 9 is a face view of another form showing the order blank at one side of the envelop, Fig. 10 is an edge view of the same, Fig. 11 is a face view of another form showing a plurality of envelops and order blanks arranged in the same sheet, Fig. 12 is an edge view of the same, and Fig. 13 is a view 70 of an open book showing the leaf bound therein.

In the drawings I have illustrated several forms of the invention as it is evident that the idea may be carried out in various ways and the different combinations which may be evolved are almost unlimited. In view of this last fact it is deemed advisable and necessary to illustrate in a general way some of the different forms which 80 may be employed in applying the invention without departing from the spirit thereof or deviating from the underlying principle.

In the various forms, certain constructive elements are substantially the same in each. 85

Reference is had to a sheet 1 having along one edge a binding portion 2 which is secured in the book or catalogue. At the upper portion of the sheet of each form, permanent space 3 is provided in which information or advertising matter which it is desired to retain in the book may be printed. The space 3 may assume various sizes and forms and could be entirely eliminated if desired. The various forms will now be described in detail, the reference numbers hereinbefore given being used to designate the same parts to which they have been applied.

In Figs. 1 to 4 two forms are illustrated which are quite similar. Contiguous to the binding portion or strip 2 a line of perforations or a weakened line 4 is provided extending from the bottom of the sheet up to the portion 3 where it intersects with a line of perforations or a weakened line 5 extending across the sheet below the portion 3 to the outer edge.

In Figs. 1 and 2 an envelop section or portion 6 is folded upon the face of the sheet, the fold being contiguous with the bottom 110 edge of the sheet and the sides being contiguous with the perforations or line 4 and

the outer edge of the sheet. Adhesive material 7 is applied along the sides as shown so that the section 6 is fastened upon the sheet, thus forming an envelop combined with the sheet. Figs. 3 and 4 show the same form except that the portion 6 is folded upon the under side of the sheet.

It will be noted that the portion 6 does not extend over the binding portion 2 and thus only one thickness or ply is bound in the book. Coincident with the top of the section 6, a line 8 is produced across the sheet indicating that a flap 9 is to be folded thereon. This flap is produced by the provision of a line of perforations or weakened line 10 extending across the page or sheet at a distance above the section consistent with the depth of flap desired. The flap 9 may be straight across its edge or the line 10 may be omitted and the contour of a line 11 adopted, this being optional.

The line 10 extends from a point of intersection with the line 4, to the outer edge of the sheet. Thus between the lines 5 and 25 10 and the line 4 and the outer edge of the sheet a portion 12 is defined, which portion I have elected to call, merely for the purpose of illustration, an order blank.

From the foregoing it is apparent that a sheet or page having a binding strip or portion along its inner edge, a permanent space or portion at the upper part of the sheet, an envelop formed from and combined with the sheet, and a defined portion between the envelop and the permanent portion is produced. It is further discernible that by tearing along the lines 4 and 5 the envelop and the portion 12 may be readily detached from the balance of the sheet which is left intact in the book in which the sheet is bound. Now by tearing along the lines 10 or 11 the envelop is separated from the portion 12 which may be placed in the envelop and the flap 9 folded down and suitably sealed.

I feel that it should be clearly understood that the section 6 is folded upon, and secured to the sheet prior to its arrival in the hands of the party who is to tear the envelop from the sheet; also all printed matter such as 50 instructions, advertisements, and information is printed upon the parts prior to binding the sheet in a book or catalogue.

As an illustration of the utility of the sheet, reference is had to Figs. 1 and 3. The sheet shown is of such size as to conform to the pages of a magazine. The portion 3 has printed thereon advertising matter and other data relative to the use of the order 60 blank 12 and the envelop. On the portion 12 a suitable order blank is printed and on the envelop the address of the advertiser is printed. The sheet is complete with a regular completed envelop integral therewith and 65 is bound into a magazine or other book as

one of the pages thereof. A reader upon opening the magazine or book and turning to this page finds an advertisement and an order blank and an envelop in connected order ready for immediate use. Said reader has merely to tear the blank and envelop from the page, place the blank in the envelop, seal the latter and drop it in the mail. The order blank may be filled in by the reader either before or after tearing it from the sheet. It will be noted that the binding, or other pages of the book are not disturbed, and the portion 3 with the matter printed thereon is retained in the book.

Instead of binding the sheet in a book it may be used as an insert between adjacent pages of a book or catalogue. It is also pointed out that sheets of different colors may be employed, a certain color being used in a certain publication or employed in a catalogue sent to a certain State. In this way the advertiser may know definitely by the color of the envelop received, the particular medium that reached the customer.

In Figs. 5 and 6 the same parts are present and in addition added advertising space is secured by providing an elongated portion 14 between the line of perforations 4 and the binding portion 2. The section 6 may be folded against the face or under side 95 of the sheet as indicated in Fig. 6. This form leaves a greater portion of the page in the book after the envelop and blank are detached, than is left in the first forms described.

In Figs. 7 and 8 the parts are the same as in Fig. 1 except the section 6 and the lines 10 and 11 are omitted. In this instance the sheet is to be of material suitable for post cards, and a folding postal card 15 produced. The order blank 2 is divided from the balance of the card by a line 16 on which the card is folded after being torn from the sheet.

Figs. 9 and 10 present a form wherein the order blank portion 17 is located at one side 110 in the same way as in Figs 1 to 4. In this form the portion 3 is greater than in the others. The line of perforations 4 extends thereto and joins with a line 50 similar to 115 the line 5 so that the order blank may be torn out. A line of perforations 18 bisects the portion 17 and the envelop and intersects with the lines 10 and 11. This form gives a generous space for permanent matter to be retained in the book.

In some cases it may be desirable to incorporate a plurality of blanks and envelops with a sheet and such a form is illustrated in Figs. 11 and 12. This form associates the blank 20 and envelop 21 in a manner similar to the form in Fig. 9, but with a flap 22 formed by the outer side edge portion of the sheet. Two sets are shown, the blanks being defined by the lines of perforations 23 130

and 24 respectively, which separate them from the binding portion 2 and the portion 3. The line 24 extends from the upper end of the line 23 to the outer edge of the page. The section 6 is made long enough for two envelopes, and an adhesive is applied as indicated at 25. A line of perforations 26 divides the two envelopes and the two blanks from each other; while a line of perforations 27 separates the envelopes from the blanks as shown. It is obvious that one envelop and blank may be torn from the sheet and used and the other preserved for future use, or both sets of blanks and envelopes may be detached and used.

While I have shown perforations and indented lines as a means for detachably connecting the parts it is to be understood that any suitable provision whereby the blank and envelop may be readily detached from the sheet may be made, and the term "weakened line" is intended to convey this meaning.

Too much stress can not be brought to bear upon the fact that the order blank portion and the envelop are preferably integral parts of the sheet, but it is to be understood that the section 6 may be a separate piece suitably secured on the sheet. It is old in this art to combine an order blank and an envelop, both in integral and detachable relation, but invariably the forming of the envelop has fallen upon the writer or user, and in no case has a complete envelop detachably connected to an order blank and both detachably connected to a page of a book, been placed in the hands of the user so that he is not called upon to paste, moisten or otherwise form the envelop.

As an article of manufacture a book page comprising an order blank and a complete envelop ready for immediate use without preliminary forming or securing of parts together, and detachably associated both with each other and with the book page, is a departure from the art and one of the features of this invention.

What I claim, is:

1. A leaf for books and the like comprising a sheet having a binding portion extending along one edge, a permanent portion bearing advertising matter and a portion adapted to be detached from the sheet, said detachable portion including an order

blank bearing memorandum peculiar to the advertisement of the permanent portion, and also a part prepared for mailing with the order blank and bearing an address relating to the advertisement of the permanent portion.

60

2. A leaf for books and the like comprising a sheet having a binding portion extending along one side edge thereof, a permanent portion bearing advertising matter, and a portion adapted to be detached from the sheet, said portion of the sheet being divided into two parts by a weakened line, one of said parts constituting an order blank and bearing memorandum peculiar to the advertisement of the permanent portion, 70 and the other of said parts being folded upon itself and the folded portions being secured together to form an envelop.

3. A book leaf or insert comprising a single sheet having a binding portion along 75 one side and provided with a weakened line parallel to the binding portion and having a weakened line extending from the first weakened line across the sheet, said weakened lines defining a portion of the sheet, 80 the said defined portion of the sheet being divided into two sections by a third weakened line and one of said sections of the sheet having an envelop constructed thereon and also provided with a portion forming a flap for the envelop.

4. A book leaf comprising a sheet having a binding portion along one side and provided with converging weakened lines at an angle to each other and each extending to 90 a different edge of the sheet, a portion of the sheet being defined from the remainder of the sheet by said weakened lines and made detachable thereby, said defined portion of the sheet being provided with a 95 weakened line dividing it into two sections one of which has a completed envelop formed therein and the other section being arranged as an order blank.

In testimony whereof I have signed my 100 name to this specification in the presence of two subscribing witnesses.

HENRY SEELIGSON.
